US00D924891S

(12) **United States Design Patent** (10) Patent No.: **US D924,891 S**
Hapka et al. (45) Date of Patent: **** Jul. 13, 2021**

(54) **DISPLAY SCREEN OR PORTION THEREOF WITH GRAPHICAL USER INTERFACE**

(71) Applicant: **Johnson Controls Technology Company**, Auburn Hills, MI (US)

(72) Inventors: **Benjamin W. Hapka**, Germantown, WI (US); **Patrick E. Harder**, Hartland, WI (US); **William Schroeder**, Brookfield, WI (US)

(73) Assignee: **Johnson Controls Technology Company**, Auburn Hills, MI (US)

(**) Term: **15 Years**

(21) Appl. No.: **29/700,546**

(22) Filed: **Aug. 2, 2019**

Related U.S. Application Data

(63) Continuation of application No. 29/635,547, filed on Jan. 31, 2018, now Pat. No. Des. 857,035, which is a continuation-in-part of application No. 29/611,064, filed on Jul. 18, 2017, now Pat. No. Des. 886,847, which is a continuation-in-part of application No. 29/601,699, filed on Apr. 25, 2017, now Pat. No. Des. 867,374, which is a continuation of application No. 29/487,827, filed on Apr. 11, 2014, now Pat. No. Des. 788,785.

CLAIM

We claim the ornamental design for a display screen or portion thereof with graphical user interface, as shown and described.

DESCRIPTION

The FIGURE is a front view of a display screen or portion thereof with a graphical user interface.

The outermost broken lines in the figures illustrate a display screen or portion thereof and form no part of the claimed design. The other broken lines in the figures illustrate portions of the graphical user interface that form no part of the claimed design.

1 Claim, 1 Drawing Sheet
